CLAIM

The ornamental design for an artist's implement container, as shown and described.

DESCRIPTION

FIG. 1 is a front side elevational view of an artist's implement container;

FIG. 2 is a rear side elevational view thereof;

FIG. 3 is a right side elevational view thereof;

FIG. 4 is a left side, elevational view thereof;

FIG. 5 is a top plan view thereof;

FIG. 6 is a bottom plan view thereof;

FIG. 7 is a top perspective view; and,

FIG. 8 is a bottom perspective view.

The broken lines depict portions of the artist's implement container that form no part of the claimed design.
